UNITED STATES PATENT OFFICE

HARRY W. DYER, OF NEW YORK, N. Y.

COMPRESSOR PUMP

Original application filed March 24, 1928, Serial No. 264,488. Divided and this application filed October 16, 1929. Serial No. 400,102.

This invention relates to compressor pumps of a type commonly used in refrigerating systems and has for an object to provide a compressor with sleeve valves, a compressor which is double acting and balanced in its action and a compressor which is compact, capable of running at comparatively high speed and is easy to manufacture. Other objects of the invention will appear 10 from the following specification and the accompanying drawings, in which, Fig. 1, is a plan view, partly in section, showing one form of the compressor pump, Fig. 2, is a side elevation, partly in section, corresponding 15 with Fig. 1, Fig. 3, is a transverse sectional elevation of the compressor shown in Fig. 1 and Fig. 4 is a longitudinal sectional view of a modified form of compressor embodying my invention.

20 This compressor comprises a central driving shaft with a cylinder disposed on either side thereof having pistons connected to an eccentric on the shaft for reciprocating movement. The cylinders are composed of a 25 length of tubing with suitable caps at the ends and with a transverse aperture to provide working space for the drive shaft and eccentrics. A valve sleeve surrounds the cylinder and is operatively connected with the driving 30 shaft by an eccentric to open and close the ports to the cylinder as the compressor is operated. This compressor is preferably mounted to operate in an oil bath so that the moving parts are thoroughly lubricated.

35 This application is a division from my co-pending application, Serial No. 264,488, filed March 24, 1928.

In the drawings selected to show one form 40 of the invention, the compressor pump comprises the base 24 to which the cover 61 is secured on a gasket making a sealed construction. The pump cylinders are secured to the base by the flanges 62 and 63. The pump is double ended and symmetrical about the centre line of the shaft, corresponding parts being used in each end.

The cylinder proper comprises a tube 72 supported and aligned by the end caps 70 and these caps are rigidly secured at 71 to the 50 outer shell 64. The piston 65 operating in

the tube 72 has an extension 66 formed with a slot 67 in which the eccentric 68 on the shaft 69 operatively engages the piston.

A sleeve valve 73 is arranged to slide longitudinally on the cylinder tube 72 thereby 55 providing a valve action for the pump. The eccentric 78 on shaft 69, Fig. 3, engages the eccentric rod 77 which connects to the stud 75 at 76. This stud moves in the slot 74 and is rigidly secured to sleeve 73 whereby the 60 sleeve is reciprocated by the rotation of shaft 69.

The piston of the opposing cylinder is operated by eccentric 91 and the sleeve valve is operated by the eccentric 80, connecting 65 rod 79 and stud 75. Sleeve bearings are provided for the shaft 69 as at 81-82, and the bearing 81 is provided with holes 83 whereby oil can flow into the cylinders and keep the mechanism immersed in oil. The shaft 70 69 terminates in a coupling 84 for connecting to the motor shaft. An adjustable seal is provided at 85 to prevent leakage of oil at the shaft outlet.

In the position of the valve as shown in 75 Fig. 1, an outlet is provided in the end walls of the cylinder at 86, in alignment with the port 87. On the opposite side of the cylinder a corresponding aperture aligns with the port 89. In this position a port in the sleeve valve 80 73 aligns with port 87 and the port 89 is closed. When the piston and sleeve move to the opposite position the port 87 is closed and port 88 in the sleeve aligns with port 89 establishing communication between the 85 pipe 90 and the cylinder. Pipe 90 connects with the pipe 36 as indicated in dotted outline in Fig. 3.

It is apparent that as the piston moves inwards and creates a suction in the cylinder, 90 the liquid or gas in pipe 36 is drawn into the cylinder through intake port 90 and 89. On the return of the piston port 88 is closed, the material is compressed and at the end of the stroke the cylinder is opened through outlet port 87 thus discharging the material 95 under pressure into the chamber *d* and to the pipe 27 to be circulated by the discharge from the compressor.

It will be noted from Fig. 3, that the 100

pump housing may be filled with oil up to the line *e* when resting on base 24, which insures perfect lubrication and the space *d* above this line is occupied by the material discharged from the ports 87 in line with the outlet 27.

5 The modified form of pump shown in Fig. 4, has certain parts identical with the pump described and similarly referenced. In this construction the eccentric rods for operating the sleeve valves are eliminated and instead the sleeve valve is continuous between the cylinders and operated directly by eccentrics on the pump shaft.

The end caps 70 are screwed into the outer tube or casing 102 at 101 so that these caps securely engage the cylinder tube 72. The piston 65—65 as shown are solidly connected by the stem 107 which is transversely slotted to receive the eccentric 106 on shaft 69, or they may be separately connected as in Fig. 3. 15 The tubes 73 and 102 are cut away at 103 to provide operating space for the eccentrics 104 and the flanged bearing 105 which has a transverse slot and is secured to the sleeve 73. The eccentric 104 operates in the slot in 105. 20 The sleeve 73 extends between the cylinders and slides with the movement of the pistons to control the parts to the cylinder as has been described. The pump mechanism is supported in a frame 108 having ports 87 and 30 89 connecting with the cylinders.

Having thus described my invention, I claim:

1. In a compressor as described, the combination of a tube having caps on each end and a transverse aperture, a shaft with an eccentric operating in said aperture, a piston in each end of said tube connected with said eccentric and a sleeve on the exterior of said tube operatively connected with said shaft to be slid over said tube and to open and close ports therein.

2. In a compressor, the combination of a tube having caps on each end and a transverse aperture, a sleeve sliding on said tube, and opening and closing ports therein, an outer casing enclosing said sleeve and connecting said caps, an operating shaft mounted in said outer casing and passing through the aperture in said tube, an eccentric on said shaft, a piston in each end of said tube connected with said eccentric and means operatively connecting said sleeve with said shaft.

3. In a compressor, the combination of a tube having caps on each end and a transverse aperture, a sleeve sliding on said tube, and opening and closing ports therein, an outer casing enclosing said sleeve and connecting said caps, an operating shaft mounted in said outer casing and passing through the aperture in said tube, an eccentric on said shaft, a piston in each end of said tube connected with said eccentric and a second eccentric on said shaft arranged to slide said sleeve.

4. In a compressor, the combination of an outer casing a pair of caps supported in alignment by said casing, a cylindrical tube having its ends closed by said caps and positioned by said caps, a sleeve sliding on said tube, and arranged to open and close ports in said tube, a piston in each end of said tube, a shaft operatively connected with said pistons mounted in said outer casing and an eccentric connecting said shaft with said sleeve. 70

5. In a compressor, the combination of a pair of cylinders in axial alignment having ports in their walls, an operating shaft mounted on the transverse center of said cylinders, an eccentric on said shaft, a piston in each cylinder connected with said eccentric, an outer sleeve on said cylinders arranged to open and close said ports and means operatively connecting said sleeve with said shaft. 75

6. In a compressor, the combination of a tube having a cap on its outer end, a sleeve sliding on said tube and opening and closing ports therein, an outer casing enclosing said sleeve and holding said cap in place, an operating shaft mounted in said outer casing, an eccentric on said shaft, a piston in said tube connected with said eccentric and means operatively connecting said sleeve with said shaft. 85

In testimony whereof I affix my signature. 90
